UNITED STATES PATENT OFFICE

170,721

PANTY GIRDLE

Leonard A. Rosner, Great Neck, N. Y., assignor
to Even-Pul Foundations, Inc., New York, N. Y., a corporation of New York

Application August 18, 1952, Serial No. 21,089

Term of patent 3½ years

(Cl. D20—2)

To all whom it may concern:

Be it known that I, Leonard A. Rosner, a citizen of the United States, residing at 7 Carey Road, Great Neck, in the county of Nassau and State of New York, have invented a new, original, and ornamental Design for a Panty Girdle, of which the following is a specification, reference being had to the accompanying drawing, forming part thereof.

I claim:

The ornamental design for a panty girdle, as shown.

LEONARD A. ROSNER.
